APPARATUS FOR THE MANUFACTURE OF
POTTERY

William J. Miller, Swissvale, Pa.

Application July 14, 1933, Serial No. 680,483

39 Claims. (Cl. 25—22)

This invention relates to apparatus for the manufacture of high quality table pottery ware, such as plates, cups and saucers and more particularly to improved methods and means for segregating charges of clay from a mass, pre-shaping blanks therefrom and applying, securing and shaping the blanks on absorbent molds for subsequent jiggering to final finish and polish.

The objects are to reduce manual labor required; insure continuity of production; reduce clay wastage and the percentage of defective ware; improve the quality and quantity of the ware produced and generally reduce production costs.

15 The present invention contemplates apparatus operable for supplying at convenient, and if desired, irregular intervals, semi-conditioned clay masses to a reserve hopper; progressing it into and through conditioning, column forming 20 and progressing apparatus; measuring and severing predetermined length slugs therefrom, each containing a multiple of charges, to provide a reserve supply; determining the slug length, instant of and frequency of slug production by the volume of clay withdrawn in the 25 production of a multiple of charges; welding the slug ends together and smoothing the weld; successively severing portions from the slug and controlling the volume of each portion by the 30 volume withdrawn in preceding charge forming operations; depositing the portions in a stabilizing reserve well; applying a substantial pressure to the clay in the well to amalgamate it with the residue therein and progress it through an 35 orifice into a charge measuring chamber; measuring and forming a charge; limiting the volume progressed by the capacity of the chamber; establishing said capacity by positioning one wall of said chamber in predetermined position; 40 maintaining a reserve supply in said well; controlling the supply of clay thereto by the volume of the reserve supply remaining in the well and by the volume of the preceding charge withdrawn; severing the charge at a predetermined 45 point from its source of supply; transferring the charge to a forming station; preshaping the charge on all surfaces into a blank of predetermined configuration and size closely approaching or bearing a distinct relation to the finished 50 ware, including reducing the cross-sectional thickness of the charge or blank; determining the water content of each surface of the blank; holding the blank against a shaped permeable form by suction through the form while transferring and applying the blank to the surface

of an absorbent or permeable mold; applying and securing the blank in predetermined angular position and uniform concentric bulk distribution to the mold while held by said form; progressively spreading the blank over the mold 5 from center to periphery by pressing it between the form, a stationary permeable matrix, and a moveable absorbent and/or permeable mold until the brim is extended, the surface contoured and the thickness established to substantially coincide with that of the finished ware; repelling the shaped ware from the matrix and form by forcing air under pressure through the permeable walls of the matrix and form, and suction to the under side of the mold, substantially at the instant of recession of mold from matrix and form; transferring the mold and shaped ware to a 10 finishing station; rotating the shaped ware surface secured to the mold against a profile tool to finally finish and polish the surface and brim, 15 thereafter drying the ware while still on the mold.

In the drawings:

Figure 1 is a sectional elevation on line I—I, Fig. 2, showing the main parts of an apparatus 25 embodying my invention;

Fig. 2 is a plan view of the apparatus;

Fig. 3 is a detail of a retarder for the feeder belt of the apparatus;

Fig. 4 is a section on line IV—IV, Fig. 2; and 30

Fig. 5 is an enlarged view of a portion of Fig. 1.

In Figs. 1, 4 and 5, I show a frame A with cross members B provided with a series of accurately spaced holes B₁ for dowls by which are secured to and positioned on the frame a conditioning and extruding apparatus C, a slug measuring and segregating apparatus D, a clay supply reserve or stabilizing and compacting device E, a charge measuring apparatus F, a blank forming apparatus G, a blank applying and conforming apparatus H, a treating apparatus J, and a charge segregating, forming and conveying turret K, these several apparatus constituting one line of a contemplated multiple of parallel lines 35 of production. Frame A also houses mold conveying apparatus L and mold and former operating apparatus M common to all lines of production.

Molds 1 positioned in seats 1a on members 1b of trays 2 are intermittently progressed along track 2a by pawl 3 on lever 4 oscillated by cam 5 on drive shaft 6, to a position adjacent the apparatus H and M and thereafter to a synchronized automatic profiling apparatus (not shown). 50 55

Mold 1 is lifted from seat 1a against a matrix 12 by a chuck 7 adjustably secured to a crosshead 8, by means of a toggle joint 9, 9a, operated through a link 10 by a cam 11. Semi-conditioned clay is fed into a hopper 13 and finally conditioned in the screw extruder C, then progressed through a die 14 as a column by means of an electric motor 15 controlled by relay 16, contacts 17, 18 and anchor switch 19, said motor driving the screw of the extruder. When a belt 20 advances the column 21 a predetermined distance, cam 22 rotating in unison with the belt 20 lifts the anchor 19 and operates a cutter 23 to part and release a slug of predetermined length from the tail 24 of the column in the die 14 and permits it to gravitate on rollers 25 towards, collide with and weld to the preceding slug 27 (Fig. 5), the weld being smoothed when drawn between rollers 27a; further progression of belt 20 causes a pin 26 on cam 22 to shift the anchor 19 to right against the contact 18 to start the motor 15 and extrude a fresh column of clay over rollers 25 until the end contacts with and shifts anchor 19 to left against adjustable contact 17 to stop motor 15 and extruder C.

Thus clay slugs are extruded, severed and conveyed by measuring device D at the same rate as used by the reserve or stabilizing device E. The conditioning device C, slug forming device D, and stabilizing device E, together, provide a reserve clay supply to insure uninterrupted operation. To control the intensity of impact between slugs 21 and 27, rollers 25 are connected with retarders, for example fluid pumps, Fig. 3, having the circulation restricted by a valve 28.

A crosshead 29 is reciprocated vertically on guides 30 by cam 11 through link 10, crank 9a and link 9b and through bolts 31a carries a plate 31 which houses a bushing 32 in threaded engagement therewith. A housing 33 fixed to the frame A has a rectangular reserve well 34 in which a ram 35 is reciprocated by the plate 31 through a stem 36, the adjustable bushing 32, nuts 37, and a spring 38. A bracket 39 secured 40 to stem 36 loosely embraces and reciprocates a rack bar 41 which engages a gear 42 driving a roller 43 through internal ratchet and pawl (not shown) to progress the belt 20 and slug 27 intermittently to left only. A spring 47 and nuts 50 threaded on the bar 41 provide a resilient and adjustable stroke of the same.

As ram 35 descends it shears off protruding end of slug 27, and progresses the clay through a port 44 into a circular chamber 45 of the disk shaped 55 turret K having teeth 46 for its rotation, until the chamber 45 is filled, then spring 38 yields, thus arresting descent of the ram 35 and rack 41; meantime, a pawl 40 on a stem 49a has locked the gear 42 to temporarily prevent advance of 50 slug 27. Upon elevation of crosshead 29, the spring 47 is compressed leaving the rack 41 stationary until at the end of the elevation of the bracket 39 it lifts the stem with the pawl 40. The spring 47 then advances slug 27 to the extent 65 to which the ram 35 has descended, so that as less clay remains in the well, more clay is deposited therein, and vice-versa. As ram 35 descends, a former 48 is elevated into the chamber 45 through a lever 49 and pitman 50 actuated 70 from the plate 31, a predetermined distance adjustable while in operation through a screw similar to screw 51, Fig. 4. The former determines the diameter, lower contour and bulk of the charge, and it enables the chambers 48 in the 75 turret to be filled to less than capacity by any

desired extent. After retraction of the former 48, a one-way rack pawl 52 operated by the lever 4 and pivoted to crossbar 53, engages the teeth 46 of turret K to turn it counter-clockwise by one division to shear the charge from the mass 5 by the action of a grid 44a, and carry it to pre-forming position G. A lock 54 operated by the pawl 52 at the termination of its travel locates and holds the turret 46 stationary, while an upper former 55, Fig. 4, and a lower former 56, 10 advance into the chamber 45 to contour both surfaces of the blank 57, the degree of pressure applied being adjustable through nuts 58 and spring 59 on a pitman 59a. Replaceable bushings 57a facilitate substitution of various brim shape and diameter blank formation, and exchangeable liners 57b between the housing and its removable base 33a facilitate substitution of various length bushings, whereby the effective depth of the 15 chamber may be varied. 20

Blank 57 is next brought under a final former 60 adapted to enter the chamber 45 when it reaches position H where the blank is transferred, conformed and secured to the surface of the mold 1 through matrix 12 and the former 25 60. Former 60 is reciprocated by the crosshead 29 through a hollow stem 60a which extends through a bushing 60b and is threaded and grooved for applying a nut 60c above, and a pressure relief collar 60d below the bushing 60b. 30 Collar 60d houses a series of adjustable spring pressed balls 60e which seat in the groove of stem 60a. When excess pressure is applied they release, thus controlling maximum pressure application and also avoiding breakage. Bushing 60b serves to adjust the lowermost extent of travel of former 60 thereby determining the thickness of the central portion of the formed ware and the threaded stem of the chuck 7 determines the thickness of the brim portion of the 40 formed ware, by enabling the chuck to be vertically adjusted in the crosshead 8 which has an internally threaded opening receiving said stem. At position J, chamber 45 may be cleaned and treated to prepare it for a subsequent charge. 45 Thereafter mold 1 is transferred to final finishing and polishing apparatus. The faces of the blank are preferably contoured convex to facilitate spreading and to insure against entrapping air between the clay and the mold, avoid folds, 50 etc.

The clay contacting faces of matrix 12, ram 35, formers 48, 60, 55 and 56 are of permeable material and their opposite faces are chambered and in communication with a source of sub and super atmospheric pressure, controlled by adjustable cam operated valves not shown, to control clay adhesion to and repulsion from these surfaces. During transfer of the blank from chamber 45 to mold 1, sub-atmospheric pressure may 60 be admitted through the face of former 60 to attract and hold the blank thereto, thus insuring proper blank placement. Also, by applying sub or super atmospheric pressure of predetermined pressure, the instant and duration of application 65 to the clay through the permeable faces of formers 48, 55, 56 and 60, during and/or following the forming operation, the water content of each face of the blank may be predetermined prior to application to the mold. 70

The formers are arranged to extract moisture from the clay by squeezing, or by the combined action of squeezing and suction, the extracted water entering the pores of the permeable clay contacting surface of the formers. This may 75

occur incident to any stage in the processing where the clay is operated upon by permeable formers with or without suction connections. By extracting water from the clay charge, the tendency toward plastic deformation is reduced, particularly during transfer from one position to another when suspended by its brim. Obviously, the extraction of water will shorten the subsequent drying time required.

10 The blank brim is compacted against and defined and supported by the chamber wall to facilitate transportation and concentric application to the mold without distortion, thus insuring uniform radial spread and final concentric 15 regular outlined brim in the formed ware, the large diameter and thin regular section also contributing towards said result. I thus dispense in the subsequent jiggering operation, with trimming off and discarding the irregular 20 excess brim resulting from applying irregular compact unformed charges, unguided, direct to the mold.

While I have shown and described the preferred embodiment of my invention, I wish it to be understood that I do not confine myself to the precise details of construction herein set forth, by way of illustration; it is apparent that many changes and variations may be made therein, by those skilled in the art, without departing from 30 the spirit of the invention, or exceeding the scope of the appended claims.

I claim as my invention:—

1. In apparatus for manufacturing pottery ware, a ware-forming mold, a chamber remote 35 from the mold, means for filling said chamber with conditioned clay from a supply thereof, means for segregating the mass in the chamber from the supply, each mass comprising a mold charge, and means for varying the position of 40 one wall of the chamber to thereby measure the quantity of clay comprised in each charge.

2. In apparatus for manufacturing pottery ware, a chamber, means for supplying conditioned clay to said chamber, a bottom former 45 remote from the mold on which the ware is formed, said former being adapted to reciprocate in said chamber, means for determining the limit of reciprocation of said former to thereby vary the depth of the clay mass in the chamber, and means for segregating the mass from 50 its supply.

3. In apparatus for manufacturing pottery ware, a reserve well, means for progressing a mass of conditioned clay to a point adjacent said well, 55 means for severing portions from the end of the mass and compacting the portions into said well, means for segregating mold charges from the mass in said well, and means for maintaining the volume of input to said well equal to the volume of output.

4. In apparatus for manufacturing pottery ware, a well, means for conditioning and extruding clay in the form of a column, a conveyor adapted to convey the column to a point 65 adjacent said well, means for segregating slugs from the end of the column as it is progressed towards said well, means for segregating portions from the slug and compacting them into said well, means for segregating charges from the 70 mass in the well, and means for regulating the travel of the conveyor to thereby control the supply of clay to the well in proportion to the rate of charge segregation and withdrawal of clay from the well.

75 5. In apparatus for manufacturing pottery

ware, a charge measuring and segregating apparatus including means for extruding clay in the form of a column, means for severing portions from the column to form clay slugs, a reserve well of sufficient capacity to hold an amount of clay for several charges, means for feeding the slugs to the well, and means for automatically controlling the rate of extrusion in proportion to the quantity of clay supplied to the said well.

6. In apparatus for manufacturing pottery 10 ware, a turret provided with a plurality of charge receiving chambers, means for intermittently rotating the turret to bring said chambers successively into charge-receiving position, means for supplying clay to each chamber as it is 15 brought into such position, a bottom adapted to reciprocate in the chamber to measure the charge, means for adjusting the reciprocation of said bottom to determine the bulk of the charge, and means operable by rotation of the turret to segregate the charge.

7. In apparatus of the class specified, a charge-receiving and measuring chamber independent of the mold on which the ware is formed, means for progressing clay into said chamber, said chamber being provided with a movable wall which is adjustable to determine the capacity of the chamber and thereby determine the bulk of clay comprised in a charge.

8. Apparatus for the manufacture of pottery 30 ware on molds comprising a disk turret provided with a series of angularly spaced chambers extending through the same, means for charging said chambers with clay, a series of preforming devices operative on the clay charges in the chambers, removable bushings in the chambers for determining the brim shape of the preformed charges, and means for rotating said turrets step-wise to bring said chambers into cooperation with the preforming devices.

9. Apparatus according to claim 10, in which the preforming devices comprise formers operative to contour both the top and bottom surfaces of the charge before its application to the mold.

10. Apparatus for the manufacture of pottery 45 ware comprising a housing, a disk turret rotatably mounted in the housing and provided with a series of angularly spaced chambers extending through the same, a base between which and the housing the turret is supported, a series of preforming devices in the housing and base operative on the clay charges in the chambers, removable bushings in the chambers for determining the brim shape of the preformed charges, and removable liners between the housing and the base for varying the effective depth of the chambers.

11. Apparatus for the manufacture of pottery 50 ware comprising a rotary disk turret provided with a series of angularly spaced chambers extending through the same, and means for charging said chambers with clay to less than their capacity by any desired extent.

12. Apparatus for the manufacture of pottery 55 ware comprising a rotary disk turret provided with a series of angularly spaced chambers extending through the same, means for charging the chambers to less than their capacity with measured amounts of clay, and a plurality of 60 formers operative successively on the measured clay charges in said chambers to preform them into blanks approximating in size and thickness to the finished ware.

13. Apparatus for the manufacture of pottery 65

ware comprising means for supporting a jiggering mold, a movable charge measuring and preforming chamber, means for bringing said chamber and mold into a predetermined positional relationship, and means for transferring the preformed charge from the chamber and applying and securing it to the mold while said relationship subsists.

14. Apparatus for the manufacture of pottery ware comprising means for supporting a jiggering mold, a chambered disk movable relatively to the mold, means for preforming in the chambers of said disk a clay blank approximating the finished ware in shape and thickness, means for bringing the chamber and mold into mutual axial alignment with the blank suspended by its rim from the chamber wall, means for transferring the thus suspended blank from the chamber to the mold while maintaining accurate registry between chamber, blank and mold, and if desired also means for applying the preshaped blank under pressure to the mold surface.

15. Apparatus for the manufacture of pottery ware comprising continuously operating ware fabricating means fed by a reserve length of clay in slug form, intermittently operating means for replenishing the reserve length, and automatic means responsive to a predetermined shortening of the reserve length to re-start the replenishing means.

16. Apparatus for the manufacture of pottery ware comprising a member having a plurality of spaced chambers and means for charging said chambers with clay to less than the capacity thereof to any desired extent.

17. Apparatus for the manufacture of pottery ware comprising a disk turret provided with a series of angularly spaced chambers extending through the same, means for variably charging said chambers with clay, a series of preforming devices operative on the clay charges in the chambers, removable bushings in the chambers for determining the brim shape of the preformed charges, and means for rotating said turrets stepwise to bring said chambers into cooperation with the preforming devices.

18. Apparatus for the manufacture of pottery ware comprising a disk turret provided with a series of angularly spaced chambers extending through the same, means for charging said chambers with clay, a series of forming devices operative on the clay charges in the chambers, means for rotating said turrets stepwise to bring said chambers into cooperation with the forming devices, and means actuated by the turret rotatting means at the end of each step to lock the turret in its next operative position.

19. Apparatus according to claim 18 comprising also means for feeding the chambers from an intermittently replenished length of clay in slug form.

20. Apparatus for the manufacture of pottery ware comprising means forming a charge forming chamber, means forming a clay reserve well, means for feeding said well with clay in slug form, a passage between the reserve well and the charge forming chamber, and a ram operative in said well to sever clay from the slug and force a quantity of clay from the same into the chamber.

21. Apparatus according to claim 20, in which the slug feed means comprises a belt, means for intermittently operating said belt to advance a portion of the slug into the well into a position

to be severed by the ram and compacted with the clay remaining in the well.

22. Apparatus for the manufacture of pottery ware comprising ware fabricating means fed by a reserve length of clay in slug form, operating means operable intermittently and independently of the ware fabricating means for preparing slugs, means for welding said slugs onto the rear end of the reserve length, and automatic means responsive to a predetermined shortening of the reserve length to re-start the slug preparing means.

23. Apparatus for the manufacture of pottery ware comprising a preshaping device operating in repeated cycles, means supporting a reserve length of clay in slug form for feeding the preshaping device, a device for extruding a column of clay, means for joining severed slugs to the reserve length, a drive for the extrusion device and severing means, and control means responsive to predetermined shortening of the reserve length to intermittently operate the said drive.

24. Apparatus for the manufacture of pottery ware comprising means forming a variable capacity chamber from which clay is intermittently removed, means supporting a reserve length of clay in slug form for feeding said chamber in an amount equal to that removed, means for extruding a column of clay, means for severing slugs from said column, means for joining the ends of said slugs, a drive for said extrusion device, and control means responsive to predetermined shortening of the reserve length to operate said drive.

25. Apparatus for the manufacture of pottery ware which comprises means forming a chamber adapted to confine a mass of clay material containing a multiple of mold charges, means for supplying said chamber with clay material comprising an extruder, a drive for said extruder whereby clay is extruded as a column, means for supporting said column, means for severing slugs from said column, means for advancing slugs to said chamber, and control means operative in response to a predetermined advance of a slug to operate said drive, and a control for said severing means operative when said drive is rendered inoperative.

26. In combination, a clay slug feeding device and means forming a chamber for the reception of a portion of the slug, means retractable from the path of the slug feed for severing said portion, control means for advancing said slug farther into said chamber when said means is retracted, means for receiving the severed portion of said clay in said chamber in the form of a mold charge, means for preshaping said charge into blank form, a mold and instrumentalities for transferring, manipulating and applying said blank to and in or on said mold.

27. Apparatus for the manufacture of pottery-ware which comprises, in combination, a plurality of molds, means for preshaping clay bodies prior to placement in or on said molds, means enabling the application of said clay bodies concentrically to said molds, and means for expanding said preshaped clay bodies on and applying said bodies to said molds.

28. Apparatus for the manufacture of pottery-ware which comprises, in combination, a plurality of molds, means for preshaping clay bodies before placement in or on said molds, and means for applying the clay to, expanding the clay on and contouring the preshaped clay to said molds.

29. Apparatus for the manufacture of pottery-

ware which comprises, in combination, a plurality of molds, means for preshaping clay bodies before placement in or on said molds, means for applying, expanding and contouring the pre-shaped clay on or to said molds, and means for releasing said clay from said applying means.

30. Apparatus for the manufacture of pottery-ware which comprises, in combination, a plurality of molds, means for preshaping clay bodies prior to placement in or on said molds, means for releasing said bodies from said preshaping means, means for automatically applying said preshaped bodies to said molds and finally forming the same thereon, and means for releasing said clay bodies from said applying means.

31. Apparatus for the manufacture of pottery-ware which comprises, in combination, a plurality of supports on which clay bodies are finally formed and dried, means for forming clay charges, means for preshaping said charges, and means for applying said preshaped charges to said supports and expanding the same thereon to final ware diameter.

32. Apparatus for manufacturing potteryware which comprises, in combination, a conveyor for molds for advancing the same toward a charging point, means for forming clay charges, means for pressing said charges to preshape the same prior to placement in or on said molds, means for applying said preshaped charges on said molds and expanding the same, and means for releasing said preshaped clay bodies from said applying means.

33. Apparatus for manufacturing potteryware which comprises, in combination, a conveyor for molds for advancing the same toward and centering the same at a charging point, means for forming clay charges, means for pressing said charges to preshape the same prior to placement in or on said molds, means for applying said preshaped charges in centered position on said molds and expanding the same, and means for releasing said preshaped clay bodies from said applying means.

45. 34. Apparatus for manufacturing potteryware which comprises, in combination, means for travelling a plurality of molds in consecutive order to a charging point, means for forming clay charges, means for preshaping said charges, means for applying preshaped clay charges to said molds, means for transferring said charges from said preshaping means to said applying means, and means for releasing said charges from said applying means.

35. Apparatus for the manufacture of pottery-ware which comprises, in combination, a plurality of molds, means for preshaping clay bodies, means for applying and expanding said preshaped clay bodies on or to the ware-forming surface of the molds, means for locating said molds with relation to said applying means whereby said clay bodies will be applied centrally of the ware-forming surface thereof, means for limiting the expansion of the clay body on the ware-forming surface of the mold, and means for releasing the clay from the applying means.

36. Apparatus for the manufacture of pottery-ware which comprises, in combination, a plurality of molds, means for moving said molds toward a charging point, means for preshaping clay bodies, means for applying preshaped clay bodies to said molds and for expanding the same thereon, and means associated with said applying means for limiting the degree of expansion of the clay bodies.

37. Apparatus for the manufacture of pottery-ware which comprises, in combination, a plurality of molds, means for preshaping clay bodies, means for applying preshaped clay bodies to said molds and expanding the same thereon, means for confining the bodies to the ware-forming surface of the molds, and means for releasing said clay from said applying means.

38. Apparatus for the manufacture of pottery-ware which comprises, in combination, means for forming clay charges, means for preshaping clay bodies from said charges, a plurality of molds, means for applying said preshaped clay bodies to said molds, means for locating said molds concentrically with relation to said applying means, said applying means being of such a nature that the preshaped clay bodies are expanded incident to application to the mold, the final brim diameter determined and the surfaces contoured and finished, and means for releasing said applying means from said clay.

39. Apparatus for manufacturing potteryware which comprises, in combination, a charge-forming apparatus adapted to feed and segregate clay bodies of predetermined bulk, means for preshaping said clay bodies, a plurality of molds, a conveyor for molds, means for advancing said molds in consecutive order to a charging point, means for applying preshaped clay bodies to said molds, whereby said clay is expanded to final form, size, shape and thickness, and means for releasing said clay from said applying means.
